MARGIN BAR FOR PRINTING CYLINDERS

Henry A. Wise Wood, New York, N. Y., assignor
to Wood Newspaper Machinery Corporation,
New York, N. Y., a corporation of Virginia

Original application March 21, 1934, Serial No.
716,560. Divided and this application November
19, 1936, Serial No. 111,561. Renewed May
19, 1939

2 Claims. (Cl. 101—378)

This is a division of my allowed application for patent, Serial No. 716,560, filed March 21, 1934.

The principal objects of this invention are to provide an arrangement for a margin bar of such a nature that if the plates are not manufactured the same length tolerances are permitted so that the margin bar follows the plate and performs its function of holding the straight edge of the plate against the cylinder; to provide means whereby the plate can "grow" on the cylinder, as it passes in and out of the impression a large number of times, without buckling the plate and causing trouble and without impairing the margin bars' function of holding down the straight edges of the plates; and to provide means whereby the tendency of the trailing edge of the plate to crowd against the margin bar while the leading edge works away from it will be avoided and both edges will be securely held against the cylinder.

Other objects and advantages of the invention will appear hereinafter.

Reference is to be had to the accompanying drawing, in which

Fig. 1 is an elevation showing half the length of the cylinder and disclosing a movable margin bar carrying a pivoted operating end;

Fig. 2 is a sectional view on the line 2—2 of Fig. 1;

Fig. 3 is a longitudinal sectional view on the line 3—3 of Fig. 1, and

Fig. 4 is a cross sectional end view, similar to Fig. 2, showing the position the parts assume as the plate cylinder rotates.

A T-slot is provided in the cylinder and on its bottom or floor 34 tapers toward the axis of the cylinder as it progresses from its outer edge toward the middle of the plate cylinder 2, as shown in Figure 3. A slide 35 is provided to fit in the T-slot in cooperation with an operating rod 39. The top 34a of the slot is parallel to the bottom in the form shown.

Each T-shaped margin bar 36 is pivotally attached to the bar 35 by a longitudinal rod 37 and rests on the ledges 26 of two plates P. The pivotal mounting of the margin bar accommodates the motions of the plates. The slide 35 is moved by means substantially the same as described in connection with the original case 716,560 filed March 21, 1934. It comprises a member 38 secured to the rod 39 by lock nuts 40. The rod 39 is shown parallel to the bottom 34 of the slot. The rod carries a spring 41, one end of which projects against a bracket 44 fastened to

the cylinder 2. The other end of the spring bears against the slide 35. A collar 43 on the rod 39 serves to move the slide 35 to the right automatically when the plates are to be unclamped. This motion elevates the margin bar 36 from the ledges 26 on the plates P and thereby releases them. When the plates are clamped the spring 41 forces the slide 35 to the left thereby bringing the margin bars 36 firmly down against the ledges 26.

On account of the longitudinal taper of the floor of the slot, each margin bar lifts, as a whole, away from the cylinder and releases the pressure which has been exerted against the two ledges 26 of each plate P when the plate is unclamped. Any longitudinal motion of this slide along the T-slot 34 will cause the slide 35 to move toward or away from the center of the cylinder.

It is well known that, as the plate cylinder rotates in the direction of the arrow shown in Fig. 4, the trailing edge of the plate necessarily bears firmly against the margin bar. This tends to make the trailing edge of the plate crowd against the margin bar while the leading edge works away from it, as shown in Fig. 4.

The object of the construction shown is to provide means whereby, regardless of the crowding of the plate against the margin bars on one side and moving away on the other, the pivoted bar 36 rests against both ledges and securely holds the straight edge of the plate against the cylinder.

It will be seen therefore that a yieldable construction is shown in the margin bar, or in the relation between two margin bars, so that, if the plates are not manufactured exactly the same length, the margin bar will hold the plate and perform its function perfectly. Also the plate can grow from passing in and out of the impression and the margin bar will yield to it so that no buckling will take place and there will be no impairment of the efficiency of the margin bar in holding down the plate. Furthermore, if adjacent plates on opposite sides of the bar are different heights on the ledge, the bar is flexible enough to cooperate with them to compensate for any difference.

Having described my invention and the advantages thereof, I do not wish to be limited to the details herein disclosed otherwise than as set forth in the claims but what I claim is:

1. The combination with a printing plate cylinder having a slot, of a slide in the slot, said slot having a slanting floor and top, whereby, as the slide is moved along the slot it will move

outwardly or inwardly in a radial direction and a margin bar pivoted to said slide and having flanges for engaging the ledges of two printing plates located adjacent thereto and on opposite sides thereof.

2. The combination with a printing plate cylinder having a T-shaped slot therein provided with a slanting floor and top surface, a slide in said slot engaging the floor, a rod passing through

the slide, an end clamp connected with said slide, whereby when the end clamp is moved longitudinally the rod and slide will be moved longitudinally and the slanting floor will cause the slide to move radially, and a margin bar pivotally mounted on the slide on a longitudinal axis and having flanges on both sides for holding printing plates.

HENRY A. WISE WOOD.
